ALLAN A. ADAMSON, OF ROCHESTER, NEW YORK, ASSIGNOR, BY MESNE ASSIGNMENTS,
TO AUTOGRAPH BOX CORPORATION, OF LIMA, OHIO, A CORPORATION OF DELA-
WARE

METHOD OF FORMING LIDS FOR CIGAR BOXES

Application filed July 17, 1928. Serial No. 293,402.

The present invention relates to a method of forming lids for cigar boxes and an object thereof is to make it possible to cover the lids for two boxes by one covering operation, thus reducing the cost of manufacture of the lids.

To this and other ends, the invention consists of certain parts and combinations of parts, all of which will be hereinafter described; the novel features being pointed out in the appended claims.

In the drawings:

Fig. 1 shows a piece of flat material from which two lids are to be made positioned upon a covering sheet;

Fig. 2 is an edge view of the parts as arranged in Fig. 1;

Fig. 3 shows one side of two lids after they have been covered and separated;

Fig. 4 is a sectional view through one of the lids on the line 4-4, Fig. 3;

Fig. 5 is a view of the other side of one of the lids; and

Fig. 6 is a perspective view of a cigar box equipped with one of the lids.

In cigar boxes the most general practice has been to produce the lid and the box separately, then attach the lid to the box by a hinging strip adhesively secured to the outer face of the box and the lid. Thereafter the box and lid are edged and by a separate operation a label is applied to the inner face of the lid.

According to this invention a lid forming member or blank 1 of wood, card board or other suitable material is provided of a size sufficient to produce two lids. This blank then has one face adhesively secured to a covering sheet 2, the covering sheet being greater in size so that marginal portions 3 are provided projecting beyond all four sides of the blank 1, these marginal projecting portions also having an adhesive applied thereto. While in this condition the lid forming member 1 and the covering blank

2 are placed in a box covering machine as, for instance, such as known commercially as a Stokes and Smith machine. This machine bends the edges or marginal portions 3 around the edges of the blank 1 and in contact with the opposite face of the blank 1 so that the blank 1 then becomes completely covered on one face and has edgings on the opposite face adjacent the edges of the latter. The covered article is now divided transversely to produce two lids, as shown in Fig. 3, each having one face entirely covered and its opposite face covered at three of its edges, the fourth edge 4 being exposed. The covered face preferably covers the outer face of a completed lid and may be provided with any suitable advertising matter as indicated at 5. A hinging strip 6 secures the lid to the box body and an edging strip 7 may be secured over the hinging strip to the rear edge 65 of the lid and the top edge of the rear wall of the cigar box body 8.

While, in this instance, the covering is shown as covering the outer face of the lid, it is apparent that the covering lid may be turned to utilize the covering as a covering for the inner face of the lid.

From the foregoing it will be seen that there has been provided a method of forming lids for cigar boxes by which two lids may be simultaneously covered and edged by one operation on a box covering machine, so that it is possible to obtain a lid with a label covering one face while three of the edges on the opposite face are edged.

What I claim as my invention and desire to secure by Letters Patent is:

1. The method of forming lids for cigar boxes which comprises providing a blank of the size sufficient to form two lids, providing a blank of a size to project beyond all four sides of the first mentioned blank, securing the two blanks together so that the second blank covers one face of the first mentioned blank and its edges extend about the edges 90

of the first mentioned blank and over the opposite face of the blank of the first mentioned blank adjacent the edges of the latter, and dividing the article thus produced transversely to provide two lids.

5 2. The method of forming lids for cigar boxes which comprises providing a rigid blank of the size sufficient to form two lids, providing a thin flexible blank to project
10 around the outer edges of said first mentioned blank, applying the thin blank to the rigid blank to cover one face of the latter and edge portions of the other face, and dividing the article thus obtained into two
15 covers.
